UNITED STATES PATENT OFFICE.

MEYER DAVIDSEN, OF PARIS, FRANCE.

CENTRIFUGAL MACHINE.

SPECIFICATION forming part of Letters Patent No. 605,087, dated June 7, 1898.

Application filed December 30, 1897. Serial No. 664,784. (No model.) Patented in France April 15, 1896, No. 255,563, and in Germany November 30, 1896, No. 95,055.

To all whom it may concern:

Be it known that I, MEYER DAVIDSEN, a subject of the King of Denmark, and a resident of Paris, in the Republic of France, have 5 invented certain new and useful Improvements in Centrifugal Machines, (for which patents have been obtained in France, No. 255,563, dated April 15, 1896, and in Germany, No. 95,055, dated November 30, 1896,) of 10 which the following is an exact specification.

This invention relates to improvements in centrifugal machines for the purpose of separating the solid matter contained in any liquid, and has for its object various improvements 15 in the construction of such machines, more especially to produce a machine capable of independent and automatic regulation during or while the machine is in continuous and constant operation.

20 In order to make my invention more clear, I refer to the accompanying drawings, in which similar letters denote similar parts throughout the different views, and in which—

Figure 1 is an elevation, partly in longitudinal section, and Figs. 2 and 3 are side views, 25 of one form of my improved apparatus, while Figs. 4, 5, and 6 illustrate in a similar manner another form of my invention.

Proceeding to describe the drawings, I 30 mark the horizontal drum *a* is provided with rotating journals *b*, tightly attached to the drum or cylinder cover and rotating in bearings *c*. Through one of these hollow journals *b*, Figs. 1 and 2, is arranged a tube *d* 35 for the purpose of conducting the material to be treated into the centrifugal apparatus, while through the other journals *b* a hollow shaft *h* is journaled, said shaft being provided with a screw *g* in such manner that the 40 velocity of the shaft *h* or the screw *g* is independent of the rotation of the drum *a*. When the drum *a* quickly rotates, the material or mass under treatment comes to lie against the inner wall of the drum, and the screw *g* 45 (in consequence of the same dipping into the material) rotates at an equal speed with the drum. If, however, the screw *g* is hindered by the arrangement of a brake device upon the shaft *h* from following the drum *a* at the 50 above-mentioned equal speed—*i. e.*, a lesser speed imparted to the screw *g*—then the solid

portion of the material under treatment is transported or carried along by said screw in a direction parallel to the longitudinal axis of the drum and eventually discharged from 55 the apertures *f*, provided for this purpose. For the discharge of the liquid, however, (from the mantle of the drum,) I provide smaller apertures *e*, as shown in Fig. 1.

Proceeding to describe, the main feature of 60 my invention—viz., the brake device herein-before-mentioned—is so constructed as to permit of varying the power of the same in an easy and convenient manner during the operation of the machinery and simultaneously 65 of regulating the velocity with which the material passes through the drum, (and is eventually ejected,) as from this speed the more or less efficient and complete ejection of the material is dependent. 70

The application of my improved brake device can, for instance, be arranged in such manner that a cheek-brake is located directly upon the screw-shaft *h*, or said brake may also be separate from the screw-shaft *h* and 75 connected with the same by a belt and pulley.

In the accompanying drawings two modified devices or constructions for the actuation of the drum *a* and the screw-shaft *h* are 80 represented, of which Figs. 1 to 3 show the same driven by means of belt and pulley *b'*. In this construction the wings of the centrifugal pump *n* are located upon the shaft *h*, the inlet and outlet of which are connected by tubing *o*, in which the control-valve *s*, Fig. 3, 85 is situated. This control-valve can be adjusted either by hand or by a governor *q*, driven from the drum *a* by means of belt and pulley *b'*. It is thus possible at any moment to change the speed of the transport-screw *g*. 90 The speed with which the material passes through the drum can therefore be optionally regulated, from which follows that the speed with which the material is ejected can be entirely controlled and adjusted. As 95 soon as the speed of the drum has been regulated and adjusted for any especial material under treatment the governor or regulator *q* can be put into action, by the employment of which governor the difference in speed between the drum and the screw is caused to be 100 constant and unvarying during the continu-

ous working of the machine. Through the hollow shaft h any desired liquid or steam can be introduced and mixed with the material under treatment.

5 The centrifugal apparatus illustrated in Figs. 4 to 6 differs only from the hereinbefore described in that an electromotor is used as driving power. In this case the armature of the electromotor v is attached to the journal 10 b , Figs. 4 and 5, of the drum a . To here produce the difference in speed between the drum a and the screw g , the armature of a dynamo is attached to the shaft h . The power or 15 strength of the dynamo-current can be controlled by a rheostat R . If a large resistance is switched in and the current from the dynamo consequently weak, the screw g would carry the material very slowly forward, while when the contrary is the case—namely, when 20 there is only a slight resistance and a powerful current—said material would be rapidly propelled by the screw g . In order that the current shall vary as little as possible, the 25 electromagnet-winding of the dynamo is switched in the chief circuit of the electromotor. (Not fully shown.) When, therefore, the motor v quickly rotates, the dynamo n will only slowly revolve and will thus effect the difference in speed. In this case 30 (similar to the adjusting of the valve s , as de-

scribed with reference to the first system) the rheostats can be adjusted by hand, while the connecting up of the motor v and the dynamo n corresponds in principle to the regulating of the speed in the manner hereinbefore described with reference to the first system, in which the brake device or governor q is employed. One portion of the current flowing from the dynamo could also be used for the purpose of driving a motor p and thereby 35 effecting the more rapid introduction of the material into the drum by the employment of another screw t , or this second motor could be used to produce the current for a suitable number of electric incandescent lamps. 40

Having thus fully described the nature of this invention, what I desire to secure by Letters Patent of the United States is—

In continuous-operating centrifugal machines, the combination with the drum a and 45 the screw g , of brake mechanism, connected to the shaft h substantially as and for the purpose hereinbefore set forth.

In testimony whereof I have signed this specification in the presence of two subscribing witnesses.

MEYER DAVIDSEN.
